Application May 28, 1935, Serial No. 23,928

15 Claims. (Cl. 204—2)

The present invention relates to a method of and means for recording in which a mark or series of marks is made upon a recording medium.

Its principal object is to provide an economical and improved recording medium and a method of marking useful for recorders of various kinds, particularly where occurrences of short time duration must be accurately recorded at high speeds, as for example in telegraph and facsimile recording.

The present available recording systems generally produce marks upon the recording medium by applying a marking material such as carbon or ink; by removing a masking material and exposing a surface of contrasting appearance; or by effecting a chemical change of the recording medium. In some of these processes the change is not immediately evident, but can be made to show the mark by a developing process. The known marking systems are generally objectionable in necessitating the maintenance of the marking ink or equivalent; in requiring careful handling of the recording medium to avoid accidental marks; in requiring a moist medium; in producing a non-permanent record, or in being limited in the speed at which marks can be made.

The present invention provides a cheap marking medium or paper which can be prepared in advance, stored and handled like ordinary paper with deterioration or change, and which is adapted to be permanently marked by simple means.

The present invention is based upon the discovery that when certain substances are subjected to a difference in electrical potential, their form may be changed from one stable allotropic form to another, the change in form occurring practically instantly and only at the point or points of application of the electrical potential. The change produced is stable in nature, not being affected by ordinary atmospheric conditions, by light or by handling. Examples of such substances are mercuric compounds such as mercuric sulphide, mercuric iodide, and mercuric oxid. For instance, when mercuric sulphide in vermillion form is applied in a thin coating to a base such as paper or metal and a current is passed therethrough, the coating changes from its vermillion form to a black form of mercuric sulphide. Both forms of the substance are stable under ordinary conditions of storing and handling and the contrast between the two forms is sharp. Similarly mercuric iodide in red form may be changed to a yellow form, due to the molecular rearrangement of its structure upon

the passage of current therethrough. Mercuric oxide in yellow form may be changed to the red form upon passage of current therethrough. The current required to effect the change in allotropic form is relatively small and hence this recording medium provides a sensitive means for producing permanent records of electrical variations. It is particularly adaptable to facsimile recording although its use is not limited thereto as will be apparent from the following detailed description of the invention taken in conjunction with the accompanying drawing in which:

Fig. 1 is a perspective view of the recording medium and a simplified marking means illustrating the principle of the invention.

Fig. 2 is a perspective view of the recording medium and a marking means illustrating the application of the invention to the well known mechanisms for obtaining continuous records of industrial operations, and

Fig. 3 is a diagrammatic view of a facsimile transmitting and recording means utilizing the present invention.

Referring to Fig. 1, there is shown a recording medium which may consist of a base or support of conducting paper, metal foil or similar conducting material coated or impregnated with an allotropic form of a mercuric sulphide. The base 1 may consist of a porous paper impregnated with a conducting substance such as an inorganic salt which has a high dissociation constant in solution. Such a conducting or semi-conducting paper is fully disclosed in a copending application of B. L. Kline, Serial No. 30,555, filed July 9, 1935, now Patent No. 2,229,091, issued January 21, 1941. Briefly, the paper is rendered conducting by impregnating it with potassium iodide, sodium bromide or a similar salt dissolved in a suitable solvent such as triethylene glycol. Of course other forms of conducting paper may be used. The allotropic compounds, as for instance, the vermillion form of mercuric sulphide may be added to the paper pulp, with a suitable sizing material, such as rosin and made in integral part of the sheet, or it may be applied to the manufactured sheet by impregnation or as a coating. For instance, the powdered cinnabar or vermillion form of mercuric sulphide may be ground in oil and applied as an ink or pigment, or it may be suspended in carbon tetrachloride and a suitable binder, such as rubber cement, or it may be suspended in alcohol containing a soluble binder such as shellac and

applied to the sheet by spraying, or in any other suitable manner.

While the recording medium is shown as a flat sheet in Fig. 1, it preferably should be of a flexible nature so that it may be rolled, as shown in Fig. 2, or applied to the surface of a cylinder, as shown in Fig. 3. While conducting paper is preferred, it is not essential, however, since with increased potentials, a non-conducting paper may be employed. The platen 2 of metal or other conducting material serves as a support for the recording medium. The pencil or stylus 3 is assumed to be movable so that it may be placed upon the recording medium or paper at any point at which it is desired to mark the paper. The platen 2 and stylus 3 are connected to a source of electric current 4 so that a current flows through the mercuric sulphide when the stylus is touched to the paper. At any such point, the mercuric sulphide will undergo an allotropic change from vermillion to black and thus any desired legend may be written upon the recording medium by suitably moving the stylus thereover. The allotropic change may be accompanied by some chemical changes of a portion of the mercuric sulphide which do not, however, prevent the alteration of color due to the change in the allotropic form of the recording medium.

Fig. 2 illustrates a type of recorder commonly used to obtain continuous records of voltage changes on power supply lines. The recording medium of the present invention has been substituted for the usual ink marking device employed on such devices. The recording medium 5 consists of a thin metal foil which has been coated with vermillion mercuric sulphide. The chart ruling and designations which may be desirable for the particular recorder may be provided by printing them in the desired color upon the vermillion, by printing the foil with the vermillion at all points except where desired for chart designations, or any other means evident to those skilled in the art.

In the form shown, the recording medium is drawn over the platen 6 and under the stylus 7 which is maintained in contact with the mercuric sulphide coating. The stylus 7 is attached to the needle extension of a voltmeter mechanism 8. The voltmeter when connected across the observed current supply line 9 causes the stylus 7 to assume different vertical positions corresponding to the voltage of the supply line. The platen 6 and the stylus 7 are connected to an electric power supply by conductors 10 and 11, which power supply in the particular embodiment shown, is the same as that being observed. The current in passing through the mercuric sulphide will change its color from vermillion to black, thus tracing a record of the movements of the stylus.

In Fig. 3 are shown two drums 12 and 13 which are assumed to be synchronously driven by the motors 15 and 16. Drum 12 is the sending instrument of a facsimile system in which the message or picture to be transmitted is scanned and the successive signals over a line depend upon the nature of the picture or message being scanned. Such a system is described in a pending application of R. J. Wise, Serial No. 23,926, filed May 28, 1935, and entitled Telegraphic transmission of intelligence, now Patent No. 2,153,858, issued April 11, 1939.

The recording medium 17 consists of a paper or similar support to which has been applied a

coating of vermillion mercuric sulphide. The stylus 18 is adapted to move longitudinally as drum 13 rotates so that the stylus traces a helical path on the recording medium.

For purposes of illustration a simple electric circuit is shown comprising a source of current 19, conductor 20, drum 12, the transmitting copy 21, the sending stylus 22, conductor 23, the receiving stylus 18, the recording medium 17, drum 13 and conductor 24. As explained in the aforesaid pending application, a current will flow through this electric circuit when the sending stylus 22 contacts a printed portion of the transmitting copy 21. This current passing through the mercuric sulphide of the recording medium 17 produces a black mark. Thus, marks are made on the recording medium corresponding to those on the transmitting copy and the transmitting copy is reproduced on the recording medium.

It will be understood that in practice, the simple circuit illustrated may for better efficiency be replaced by various arrangements for transmitting electrical impulses which are well known in the communication art.

What is claimed is:

1. The method of recording which comprises passing an electric current through selected elemental areas of a surface portion of an allotropic form of a mercuric compound in such manner as to cause said compound to change to another allotropic form and alter its color in those elemental areas through which the current is passed.

2. A method of recording which comprises applying to a base a coating of an electrically sensitive allotropic form of a mercuric compound having two allotropic forms of different color, and selectively passing electric current through selected elemental areas of said coating to effect a change in the allotropic form of the coating and alter its color in those elemental areas through which the current is passed.

3. The method of marking which comprises applying an electrical potential to a record sheet comprising an electrically conductive backing coated with vermillion mercuric sulphide and thereby changing the color of the surface of the record sheet from vermillion to black.

4. A recording medium comprising a base carrying an electric current sensitive allotropic form of a mercuric compound which alters its color when an electric current is passed through the compound.

5. A recording medium comprising an electrically conductive support carrying an electric current sensitive allotropic form of a mercuric compound which alters its color when an electric current is passed through the compound.

6. A recording medium comprising a metallic base carrying an electric current sensitive allotropic form of a mercuric compound which alters its color when an electric current is passed through the compound.

7. A recording medium comprising a base carrying an electric current sensitive allotropic form of a mercuric compound which alters its color when an electric current is passed through the compound, said compound comprising one or more of the group consisting of mercuric sulphide, mercuric iodide and mercuric oxide.

8. A recording medium comprising an electrically conductive support carrying an electric current sensitive allotropic form of mercuric compound which alters its color when an electric current is passed through the compound, said

compound comprising one or more of the group consisting of mercuric sulphide, mercuric iodide and mercuric oxide.

9. An electrosensitive recording medium comprising a support having a coating of vermillion mercuric sulphide applied thereto.

10. An electrosensitive recording medium comprising a support and a coating of vermillion mercuric iodide applied thereto.

11. An electrosensitive recording medium comprising a support and a coating of yellow mercuric oxide applied thereto.

12. An electrosensitive recording medium comprising a conductive support having applied thereto vermillion mercuric sulphide.

13. An electric recording sheet comprising an electrically conducting paper and a coating thereon of vermillion mercuric sulphide.

14. A recording medium comprising a conductive support, a coating of a lacquer on said support, said lacquer containing an electric current sensitive allotropic form of a mercuric compound which compound is convertible to another allotropic form of a different color upon passing electric current therethrough.

15. A recording medium comprising a conductive support, a coating of a lacquer on said support, said lacquer being composed of shellac in alcohol and containing vermillion mercuric sulphide which is subject to color change upon passage of an electric current therethrough.
